O. H. GARDNER, OF FULTON, NEW YORK.

Letters Patent No. 80,722, dated August 4, 1868.

IMPROVEMENT IN VISES.

The Schedule referred to in these Letters Patent and making part of the same.

TO ALL WHOM IT MAY CONCERN:

Be it known that I, O. H. GARDNER, of Fulton, in the county of Oswego, and State of New York, have invented a new and useful Improvement in Bench-Vise; and I do hereby declare that the following is a full, clear, and exact description thereof, which will enable others skilled in the art to make and use the same, reference being had to the accompanying drawings, forming part of this specification.

Figure 1 is a top view of my improved vise.

Figure 2 is a vertical section of the same, taken through the line x x , fig. 1.

Similar letters of reference indicate corresponding parts.

My invention has for its object to improve the construction of bench-vises, so as to enable them to adjust themselves to the form of the object to be held, and to enable them to be adjusted, so that the jaws may stand at any desired horizontal angle with the bench, and which shall at the same time be simple in construction and easily adjusted; and it consists in the construction and combination of the various parts, as hereinafter more fully described.

A represents the bench, to which the vise is attached. B is the rear jaw of the vise, the lower end of the shank, b^1 , of which rests and is pivoted in a socket, C, attached to the floor. To the rear side of the upper part of the shank b^1 of the rear jaw B is attached a semicircular plate, D, having a downwardly-projecting flange formed upon its curved edge, which fits over a curved shoulder formed upon a plate, E, securely attached to the bench A.

The plate E is made with a curved slot for the reception of the clamping-screw F, the head of which slides along in a recess formed upon the under side of the plate E. This enables the shank of the rear jaw to be so adjusted that the said jaw may stand at any desired horizontal angle with the bench A.

When adjusted, the shank of the rear jaw B is secured in place by turning down the nut f' upon the screw F, clamping the plate D to the plate E.

G is the front or movable jaw, the lower end of the shank, g' , of which has a ball, H, formed upon its lower end, which fits and works in a socket formed in the outer part of the cylindrical slide-bar I.

J is a spring, one end of which is secured in a recess formed in the interior of the slide-bar I, and the free end of which rests in a circular groove formed around the ball H, as shown in fig. 2. The effect of the spring J is to hold the front jaw G back from the rear jaw B, except when forced forward by the clamping-screw, for convenience in putting the object to be held into the vise or taking it out.

The slide-bar I, I prefer to form in two equal semi-cylindrical parts for convenience in placing the ball H and spring J in their places, said parts being secured to each other by screws.

The cylindrical slide-bar I passes through a hole formed in the shank b^1 of the rear jaw B for its reception, and its outer end rests upon an arm or support, b^2 , formed upon or securely attached to the forward side of the lower part of the shank b^1 , as shown in fig. 2.

The cylindrical slide-bar I is held in place, when adjusted, by a pawl, K, pivoted to the forward side of the shank b^1 , and the lower end of which enters one or the other of the notches formed in the upper side of said bar I, as shown in fig. 2.

L is the clamping-screw, which passes through a hole in the upper part of the shank g' , and screws into a long nut, M, connected with the upper part of the rear shank b^1 .

N is a saddle-washer, which is interposed between the head of the screw L and the side of the shank g' .

The forward side of the washer N is concaved, and the adjacent side of the shank g' is made curved or rounded, so that the screw L may always press squarely against the shank g' , however said shank may be turned upon the ball-and-socket joint at its lower end.

M is a long nut or socket, fitting loosely into a hole in the upper part of the shank b^1 , and which has an irregular flange or ring-projection formed upon it, which fits into a recess formed in the rear side of the shank b^1 , so that the said nut may not be revolved by turning the screw L.

O is a dog, sliding up and down upon the lower part of the shank g' of the jaw G, and the movement of which may be limited by a pin passing through a slot in said shank, as shown in fig. 2.

Upon the lower side edges of the dog O are formed downwardly-projecting flanges, which, when said dog is lowered, overlap the upper side edges of the squared outer end of the cylindrical slide-bar I, so as to prevent the movement of the said shank g' upon the socket-joint when it is desired that the jaw G should be held parallel with the jaw B.

P is a spring, attached to the outer side of the shank g' , the point of which rests against the said shank, and when the dog O is raised, springs into a hole or recess formed in said shank, and holds the said dog O suspended, allowing the jaw G to work freely upon the ball-and-socket joint formed upon the lower end of its shank g' , to adjust itself to the shape of object to be held.

I claim as new, and desire to secure by Letters Patent—

1. The combination of the spring J with the ball H, formed upon the lower end of the shank g' , and with the cylindrical slide-bar I, substantially as herein shown and described, and for the purpose set forth.
2. The combination of the sliding dog O with the shank g' of the front jaw G, and with the outer end of the cylindrical sliding bar I, substantially as herein shown and described, and for the purpose set forth.
3. The combination of the spring-catch P with the shank g' , and with the sliding dog O, substantially as herein shown and described, and for the purpose set forth.
4. The described construction of the flanged plate D, and the recessed and slotted plate E, the former being attached to the shank of the jaw B by a screw, in order to be removable, as herein shown and described.

O. H. GARDNER.
